UNITED STATES PATENT OFFICE.

GEORGE ARCHIBALD DRUCKER, OF NEW YORK, N. Y.

PORTABLE FUSE AND FUSE-BLOCK.

No. 909,165.

Specification of Letters Patent.

Patented Jan. 12, 1909.

Application filed July 14, 1908. Serial No. 443,501.

To all whom it may concern:

Be it known that I, GEORGE ARCHIBALD DRUCKER, a citizen of the United States, residing in the borough of Manhattan, city, 5 county, and State of New York, have invented a certain new and useful Improvement in Portable Fuse and Fuse-Blocks, of which the following is a full, clear, concise, and exact description.

10 My invention relates more particularly to fuses used for firing powder in connection with flash light photography and has for its objects to provide a means for increasing the intensity of the flash and thereby a larger 15 zone illumination.

A further object is to provide a fuse that may be readily adjustable and conveniently portable.

The foregoing and other features of my invention will now be described in connection with the accompanying one sheet of drawings, forming part of this specification in which I have represented my fuse embodying the improvements in the preferred form, after 25 which I shall point out more particularly in the claims those features which I believe to be new and of my own invention.

My invention consists in the features of construction, combination of elements and arrangement of parts which will be exemplified in the mechanism hereinafter described, and the scope of the application of which will be indicated in the claims.

Referring to the accompanying drawings 35 in which similar characters of reference indicate like parts throughout the several views, Figure 1 is a top view of my portable fuse and block. Fig. 2 is a longitudinal sectional elevation along the line 2 2 Fig. 1. Fig. 3 is a detail of means of securing the bifurcated fastening in the hole of the yokes. Fig. 4 is a cross section along the line 4 4 Fig. 1. Fig. 40 5 is a detail of end of receptacle for flash powder. Fig. 6 is an end view showing flash powder receptacle supported solely by the yokes.

In my invention I employ a rectangular base 1 of non-conducting material, with yokes 3 mounted thereon provided with 50 holes 5 in the bottom of the yokes extending therethrough and through the base 1. The yokes are provided with any well-known means for connecting to any electrical circuit 6. Slidably mounted on base 1 are two 55 wedges 7 which are adapted to move across the holes 5 in the yokes 3, as will be readily

seen by referring to Fig. 3. For my flash fuse I employ a trough 8 made from a piece of fiber board or any other non-conducting, non-combustible material, folded and fastened at the ends as shown in Fig. 5. This trough is wider at the base than at the opening, as will be readily understood by referring to its section, Fig. 4. In the bottom of the trough are two bifurcated fastenings 9 spaced so as to engage the holes 5 in the yokes 3. Connecting these two fastenings is a fine fuse wire 10 which passes under the horizontal portion of the bifurcated fastening and is clamped against the trough making an electrical contact with the fastening. One prong of each bifurcated fastening secures each end of the wire 10 to the trough 8, the other depends from the bottom of the trough and engages the holes 5 as before stated, and are securely fastened to the yokes by jamming between the wedges 7 and side of holes 5. The wire 10 completes the circuit between the yokes 3. In the trough or receptacle 8 I place sufficient flash powder, or proper ingredients, for the required illumination and a simple cover, not shown, is placed over the opening of the trough. I shellac the top of the bifurcated fastenings to prevent the incandescent metallic ingredients of the flash powder from accumulating around the fastenings and arcing across the gap after the fine wire is burned out. This prevents the possible consumption of more current than is required for the explosion of the powder which sometimes causes considerable trouble in the electrical circuit to which the fuse block is connected. The object of the trough being wider at the base than at the opening is to direct the flash in a thin sheet of flame which increases the illuminated zone without limiting the powder capacity.

My invention may be used with or without a smoke bag that is usually employed for interior work.

To steady the trough or flash powder receptacle on the ends, I employ pockets 12 mounted on base 1. A further object of these pockets is to close any leak that may be in the ends of the receptacle 8 and thereby prevent the powder from sissing out and igniting anything exposed to the flame. The object of the yokes is to provide a means of vertically supporting the trough 8.

In practice I use the trough 8 for only one flash and then it is thrown away: the low

cost permits this very readily. The troughs are folded in the laboratory secured on the ends and after the fine wire 10 is adjusted and secured in place by the bifurcated fastenings a sufficient amount of flash powder is put in the trough and its cover put in place. In this way the powder and fuse wire are conveniently portable and may be readily carried around from place to place. When a 10 flash is to be made I place in adjusted position my fuse block, connect with the electric circuit, open the switch, place the depending portions of the bifurcated fastenings in the holes in the base adapted to receive same, 15 clamp the wedges home, remove the cover of the trough, and everything is ready for the flash. When the switch is thrown in the fine wire melts under the current and ignites the flash powder which, being directed 20 by the long narrow opening of the trough, flashes up in a thin sheet, producing a larger zone of illumination than methods now employed.

I wish it distinctly understood that my 25 portable fuse and fuse block herein illustrated and described, is in the form in which I desire to construct it, and that any changes or variations may be made as may be convenient or desirable without departing from 30 the salient features of my invention.

Having thus fully described my invention, what I claim as new and desire to secure by Letters Patent is,—

1. A portable fuse, of the class described, 35 consisting of a trough of fiber board closed at the ends and wider at its base than at the opening, provided with a fine wire secured by fastenings to the bottom of the trough, the said fastenings depending from the outside of 40 the trough.

2. A portable fuse of the class described 45 consisting of a trough of non-combustible and non-conducting material, closed at the ends provided with a fine wire secured to the bottom of the trough by two fastenings which depend from the outside of trough.

3. A portable fuse of the class described 50 consisting of a trough of non-combustible and non-conducting material closed at the ends provided with a fine wire terminating in bifurcated fastenings which depend from the trough.

4. In a portable fuse and block of the class 55 described, in combination with a base of non-conducting material provided with two yokes mounted thereon, each yoke provided with a hole extending through the base; a trough of fiber board provided with a small wire terminating in bifurcated fastenings depending

from the trough and spaced to engage the 60 holes in the yokes, two wedges slidably mounted on the non-conducting base adapted to secure the depending fastenings of the fiber board to the yokes, and means for connecting the yokes in an electrical circuit. 65

5. In a portable fuse and fuse block of the class described, in combination, a base of non-conducting material provided with two yokes mounted thereon, each yoke provided with a hole extending therethrough and 70 through the base; a non-conducting and non-combustible receptacle adapted to engage the aforementioned yokes provided with a fine wire terminating in bifurcated 75 fastenings which fasten the wire to the receptacle and depend from its bottom and engage the holes in the aforementioned yokes; wedges slidably mounted on aforementioned non-conducting base adapted to secure the bifurcated fastenings in the yokes; means for 80 connecting the yokes in an electrical circuit.

6. In a device of the character described in combination, a base of non-conducting material provided with two yokes of conducting 85 material mounted thereon, each yoke provided with a hole in the bottom extending through the base; a receptacle for flash powder, made of non-conducting and non-combustible material, adapted to engage the aforementioned yokes provided with a cover 90 and with a fine wire terminating in bifurcated fastenings; wedges slidably mounted on the aforementioned non-conducting base adapted to secure the depending portion of the fastening in the yokes; and means to electric- 95 ally ignite the flash powder.

7. In a device of the character described, in combination, a base of non-conducting material provided with two yokes of conducting material mounted thereon, forming terminals of an electric circuit, each yoke provided with a hole extending through the base; a trough of non-conducting and non-com- 100 bustible material, closed at its ends and wider at the base than at its opening, containing 105 flash powder to be exploded; wedges slidably mounted on the aforementioned base adapted to engage the depending portions of the bifurcated fastenings in the yokes, thereby connecting in circuit the fine wire. 110

This specification signed and witnessed in 911 Flat-Iron Building, New York city, this ninth day of July, A. D., 1908.

GEORGE ARCHIBALD DRUCKER.

In the presence of—

EDWD. VAN WINKLE,
MARGUERITE ROSS.
